UNITED STATES PATENT OFFICE.

GEORGE A. GRITTON, OF VOLCANO, CALIFORNIA, ADMINISTRATOR OF
ROBERT RODGERS, DECEASED.

CHAIR.

SPECIFICATION forming part of Letters Patent No. 693,323, dated February 11, 1902.

Application filed August 15, 1901. Serial No. 72,321. (No model.)

To all whom it may concern:

Be it known that I, GEORGE A. GRITTON, a citizen of the United States, residing at Volcano, in the county of Amador and State of California, administrator of the estate of ROBERT RODGERS, deceased, late a citizen of the United States and a resident of Volcano, in the county of Amador and State of California, (as by reference to the duly-certified copy of letters of administration hereto annexed will more fully appear,) do hereby declare that ROBERT RODGERS invented a new and useful Chair, of which the following is a specification.

15 The object of the invention is to provide a chair of integral or single-stock construction wherein all of the elements thereof, including the frame, braces, and back and seat fillers and also when a rocking-chair the rockers, 20 are constructed from a single original stock or timber kerfed, sawed, or split to form the necessary elements or branches to constitute the various parts of the structure.

Further objects and advantages of the invention will appear in the following description when considered in connection with the accompanying drawings, wherein similar reference characters represent corresponding parts in all the figures, and the novel features thereof will be particularly pointed out in the appended claims, it being understood that various changes in the form, proportion, size, and minor details of construction may be resorted to without departing from the 35 spirit or sacrificing any of the advantages of the invention.

In the drawings, Figure 1 is a perspective view of a chair constructed in accordance with the invention, the form shown being a 40 rocking-chair. Fig. 2 is a detail view in perspective of the upper portion of the chair-back, showing the head-bar and the upper portions of the back-filers and indicating the manner of securing the parts together at their points of intersection. Fig. 3 is a detail view of the joint between the front seat-standards and the seat. Fig. 4 is a detail view in perspective of a portion of one of the front standards. Fig. 5 is a detail view of 45 the joint between the side braces.

The chair embodying the invention is of bent-wood construction and is preferably cut or split from an original straight stock or timber, of which the central portion in length forms the head-bar 1 at the top of the chair-back. From this point the stock with but small reduction in width (measured in a direction parallel with the plane of the back) is extended to form the back side bars 2, the bend at the junction of said side bars with 55 the head-bar being effected by cutting away the major portion of the width of the stock, as shown at 3, to form a thin web 4, which bends readily and forms a rounded and graceful corner. The side bars of the back 60 extend downward to the plane of the seat with but one intermediate reduction in thickness formed by dividing therefrom the strips, which may be comparatively light, to form the arms 5; but at the plane of the seat the side 65 portions 2 are divided into three branches to form, respectively, a rear leg 6, a seat side bar 7, and an intermediate side brace 8, the outer 70 portions 6 and 7 thus formed being comparatively heavy, while the intermediate brace is 75 light. The reduction or the division of the side bar 2 to form the elements 6, 7, and 8 is in thickness; but in addition to this one of the side bars 2 is divided in width to form branches 80 or elements 9 and 10, respectively constituting a rear seat-bar and a rear brace, said seat-bar being extended transversely between the side bars 2 and being terminally attached to that side bar which is opposite to the one from which it is formed. The seat side bars 7 are 85 extended inward at their front ends to form the front seat-bar 11, the angular bends at the front ends of the side bars being formed, as shown in Fig. 3, by reducing or recessing the stock at those points to form thin bendable webs 12, the recesses thus constructed being of such a shape as to snugly receive the slightly-reduced portions or necks 13 of the arm elements 5. The extensions of these arm elements below the plane of the seat-bars form 90 the front chair-legs 14, which may be reduced in thickness to form the side braces 15 and may be reduced in width to form the front braces 16, the lower ends of said front braces being mortised into the opposite front legs, 95 100

respectively. The side braces 15 preferably intersect the side braces 8 and may be interlocked therewith by halving to form notches 17, as shown in detail in Fig. 5, the lower ends 5 of said side braces being engaged with or mortised into other chair elements, such as the legs or rockers, according to the form of chair which is being constructed. When the chair is of the rocker type, the elements 5 to 10 14, which respectively form the arms and front legs, are extended to form rockers 18, into which are mortised the lower ends of the elements forming the rear legs 6. The connection between the lower ends of the front legs 15 14 and the front ends of the rockers 18 is formed by thin webs 19, consisting of reduced portions of the elements produced by recessing the same in thickness, as shown at 20.

It will be seen that the entire frame, including the braces of the chair, has now been described and that the rocker elements may be included or omitted, according to whether a rocker or stationary chair is to be constructed.

The back and seat fillers consist of thin 25 strips cut, respectively, from the inner and outer sides of the stock, and thereby reducing the latter in width, and constitute the outer elements 21 and the intermediate elements 22, said intermediate elements preferably being folded or re-turned upon themselves to form the loops 23 and being halved with the head-bar, as shown in detail in Fig. 2, to interlock therewith. Each of these elements is secured to the rear seat-bar at its point of 30 intersection therewith, the screws 24 being illustrated in the drawings as the means for thus attaching said parts, and beyond said rear seat-bar the elements are extended forward to form seat-filters, which are mortised at 35 their front ends into the front seat-bar, screws 25 also being shown at this point for securing said extremities in place.

What is claimed is—

1. A bent-wood chair having its back and 45 seat frames, and front and rear legs integral and cut from a single stock.

2. A bent-wood chair having its back and seat frames, side arms and front and rear legs integral and cut from a single stock.

50 3. A bent-wood chair having its back and seat frames, its front and rear legs, and its side arms integral and cut from a single stock, the front legs being formed as extensions of the side arms.

55 4. A bent-wood chair having its back and seat frames and its legs integral and formed from a single stock of which the head-bar of the back-frame forms the center.

60 5. A bent-wood chair having its back and seat frames and front and rear legs integral and formed from a single stock of which the head-bar of the back-frame forms the center, and of which the side bars of the back-frame form continuations, the stock being recessed 65 at the points of junction of the side bars with the head-bar to form pliable webs:

6. A bent-wood chair having its back and

seat frames integral and formed from a single stock, and side arms integrally connected with the side bars of the back-frame.

7. A bent-wood chair having its back and seat frames integral and formed from a single stock, and seat-filters also integral with said stock.

8. A bent-wood chair having its back and 75 seat frames integral and formed from a single stock, and also having back-filters integral with said stock.

9. A bent-wood chair having its back and seat frames integral and formed from a single 80 stock, and also having back and seat filters, one of which is formed as an extension of the other, and also integral with said stock.

10. A bent-wood chair having its back and seat frames integral and formed from a single 85 stock, and also having back and seat filters integral with and struck from said stock at the upper end of the back-frame.

11. A bent-wood chair having its back and seat frames integral and formed from a single 90 stock, and outer and intermediate back and seat filters also integral with said stock and struck respectively from the inner and outer sides thereof.

12. A bent-wood chair having its back and 95 seat frames integral and formed from a single stock which is reduced in width at opposite sides of its center to form integral back and seat filters.

13. A bent-wood chair having its back and 100 seat frames integral and formed from a single stock which is reduced in thickness at opposite sides of its center to form integral side arms.

14. A bent-wood chair having its back and 105 seat frames integral and formed from a single stock which is reduced in thickness at the junction of the back and seat frames to form integral rear legs.

15. A bent-wood chair having its back and 110 seat frames integral and formed from a single stock which is reduced in thickness at intermediate points to form integral side arms intersecting the seat-frame and extended below the frame thereof to form integral front legs, 115 said stock being also reduced at the junction of the back and seat frames to form integral rear legs.

16. A bent-wood chair having its back and 120 seat frames integral and formed from a single stock which is reduced at intermediate points to form integral side arms extended below the plane of the seat-frame to form front legs, and also reduced at the junction of the back and seat frames to form legs, the portion of 125 the stock forming said front and rear legs being further reduced to form intersecting side braces.

17. A bent-wood chair having its back and seat frames integral and formed from a single 130 stock which is reduced in thickness at the junction of the back and seat frames to form rear legs, and is reduced in width at an adjacent point to form a rear seat-bar.

18. A bent-wood chair having its back and seat frames integral and formed from a single stock of which the seat side bars are extensions of the back side bars and of which the front seat-bar consists of extensions of the seat side bars, one side member of the stock being reduced in width to form a rear seat-bar which is extended transversely and connected with the opposite side member. 45
19. A bent-wood chair having its back and seat frames integral and formed from a single looped stock of which the side bars form the side bars of back and seat frames and are extended transversely at their front ends to form the front seat-bar, one of said side members being reduced in width to form a rear seat-bar. 50
20. A bent-wood chair having its back and seat frames integral and formed from a single looped stock of which the side bars form the side bars of back and seat frames and are extended transversely at their front ends to form the front seat-bar, one of said side members being reduced in width to form a rear seat-bar, and both of said side members being reduced in thickness to form rear legs and side braces. 55
21. A bent-wood chair having its back and seat frames integral and formed from a single stock of which the side members are reduced in thickness at opposite points to form side arms and front legs, and are further reduced in thickness at their opposite points to form rear legs and side braces. 60
22. A bent-wood chair of integral construction having a stock divided longitudinally to form elements integral and connected with the stock and respectively forming back and seat frames, and front and rear legs. 65
23. A bent-wood chair of integral construction consisting of a stock divided longitudinally to form elements integral and connected with the stock, and respectively forming back and seat frames, front and rear legs, side arms, and braces. 70
24. A bent-wood chair having its back and seat frames integral and formed from a single looped stock of which the side bars are divided longitudinally to form integral elements connected with the main stock, and constituting front legs and rockers. 75
25. A bent-wood chair having its back and seat frames integral and formed from a single looped stock of which the side bars are divided longitudinally to form integral elements connected with the main stock, and constituting side arms, front legs and rockers. 80
26. A bent-wood chair having its back and seat frames, its front and rear legs, and rockers integral and formed from a single stock. 85
27. A bent-wood chair having its back and seat frames integral and formed from a single looped stock of which the side members are divided longitudinally to form elements which respectively constitute rear legs, and continuous side arms, front legs and rockers. 90
28. A bent-wood chair having its back and seat frames integral and formed from a single looped stock reduced to form integral elements constituting rear legs and side braces, also reduced to form side arms, front legs and rockers, said front legs also being reduced to form side braces intersecting the first-named side braces. 95
- In testimony that I claim the foregoing as the invention of ROBERT RODGERS I have hereto affixed my signature in the presence of two witnesses.
